F. DERDITS.

GRAB POLE.

APPLICATION FILED JAN. 14, 1916.

1,180,764.

Patented Apr. 25, 1916.

UNITED STATES PATENT OFFICE.

FRANK DERDITS, OF HOBOKEN, NEW JERSEY.

GRAB-POLE.

1,180,764.

Specification of Letters Patent. Patented Apr. 25, 1916.

Application filed January 14, 1916. Serial No. 72,151.

To all whom it may concern:

Be it known that I, FRANK DERDITS, residing in Hoboken, in the county of Hudson and State of New Jersey, have invented 5 a new and Improved Grab-Pole, of which the following is a specification.

My invention which has reference to store service appliances primarily has for its object to provide an economical, neat, easily 10 operated and effective appliance in the nature of a grab pole adapted to fetch down from high shelves, articles such as canned goods, bottles and other packages usually found in grocery and delicatessen stores, 15 and by the use of which the need of step ladders and the like for lifting articles from high shelves is done away with.

With other objects in view, that will be explained, my invention is an appliance for 20 the purposes stated that embodies the peculiar features of construction and novel arrangement of parts, hereinafter fully described, specifically pointed out in the appended claims and illustrated in the accompanying drawing, in which:

Figure 1 is a perspective view of my invention and illustrates the manner of using the same. Fig. 2 is a perspective view of the upper end of the appliance, the grab 30 members being open as shown in Fig. 2. Fig. 3 is a section of the lower portion of the pole. Fig. 4 is a vertical section of the upper end of the appliance taken practically on the line 4-4 on Fig. 2. Fig. 5 is an elevation 35 of the device, the arms being in the normal or closed position. Fig. 6 is a detail section of the fulcrum. Fig. 7 is a detail perspective of the crotch in the tension spring.

40 My improved appliance comprises a wooden pole 1, of suitable length, the upper end of which is capped by a metal ferrule or band 2. At the lower or handle end, the pole 1 has an elongated recess 3, and in the 45 said recess is pivotally mounted the inner end of a trigger lever 4, with which connects a flexible link 5 secured on the lower end 60 of a steel wire pull rod 6, that extends up through the pole and has its upper 50 end 61 extended beyond the upper end thereof, the reason for which will presently appear.

7-7 designate a pair of toggle link members and they are pivotally connected at

their lower ends, to a stud screw 9 that 55 passes into the ferruled end of the pole 1.

8-8 designate a pair of crossed toggle levers (pivotally connected by a fulcrum stud 83) whose lower ends are pivotally connected by rivet pivots 70-70 to the upper ends of the link members 7-7 which, as also the members 8-8, are preferably formed of stout strap steel.

Lever members 8-8 have their upper ends bent forwardly at right angles to form 65 grab arms 81-81 and the said arms, as is clearly shown in Figs. 2 and 3, are relatively so bent and projected from their respective members 8-8 so that their gripping faces 82-82, when the members 8-8 are opened 70 or spread, as in Fig. 2, for grabbing an article, are in practically parallel relation and in longitudinal alinement with the pole.

To keep the grab arms from slipping off an article grabbed thereby, particularly 75 cans, glass ware and the like, rubber sleeves 10 are secured thereon and to keep the said rubber sleeves from freely slipping off the said arms and to further provide for a positive gripping of the articles the outer ends 80 of the said arms are curved downwardly so that the gripping tendency of the said arms is such as to close around the article.

The upper end 61 of the pull wire terminates in a loop 62 adapted to be readily 85 slipped over the fulcrum stud 83 and by reason thereof it is obvious that when the trigger lever is pulled down the several lever members 7-7 and 8-8 are opened or spread to the position shown in Fig. 2.

11 designates a stout bow spring, one end of which projects down into a socket 12 on the upper end of the pole in which it is held clamped by the ferrule 2, as is clearly shown in Fig. 4, which also shows the spring 11 95 extending up from the pole with its free end provided with a notch-like seat 13 that extends under and interlocks with the fulcrum stud 83. By reason of providing a bow spring device and mounting it on the 100 end of the pole, as shown and described, the said member beside serving as the spring device that normally tends to close the grab arms, also serves as a stay or support for the toggle lever devices and keeps them in a positive rigid relation as they are moved to the open position by manipulating the trigger lever 4 and moved to their closed position.

tion by the said spring 11. Again, by reason of providing a spring device, as shown, a stout spring tension is at all times on the grab arms to hold them positively closed on the article grabbed thereby, and in case the spring should break, a new spring member can be readily substituted.

From the foregoing description taken in connection with the drawing, the construction, the manner of use and the advantages 10 of my invention will be readily apparent.

What I claim is:

1. In an appliance of the character described, the combination with a pole, a pair 15 of link members pivotally connected at their lower ends on a common pivot to the upper end of the pole, a pair of crossed toggle levers pivotally connected at their lower ends to the free ends of the link members, a stud 20 pivot that joins the crossed toggle levers, a spring device secured at one end to the pole and at the other end to the stud pivot on the crossed toggle levers that tends to normally move the toggle levers to their closing position, the upper ends of the crossed toggle levers being bent at right angles to form grab 25 arms, and a flexible pull that connects with the fulcrum pivot for the crossed toggle levers, said pull including a portion that extends 30 down to the handle end of the pole.

2. In an appliance of the character described, the combination with a pole, a pair 35 of toggle links pivotally connected at their lower ends to a single stud pivot on the pole, a pair of crossed toggle levers pivotally connected at their lower ends to the upper ends 40 of the toggle links that are attached to the pole, a stud pivot that forms the fulcrum for the crossed levers, said crossed levers having their upper ends bent at right angles 45 to form a pair of opposing grab members, a bow spring having an end secured to the upper end of the pole and its other end notched to slip into locked engagement with the stud pivot and a flexible pulling ele-

ment that connects at the upper end with the fulcrum stud pivot and whose lower end extends down to the handle end of the pole.

3. In an appliance of the character described, the combination with a pole, a pair 50 of toggle links pivotally connected at their lower ends to a single stud pivot on the pole, a pair of crossed toggle levers pivotally connected at their lower ends to the upper ends 55 of the toggle links that are attached to the pole, a stud pivot that forms the fulcrum for the crossed levers, said crossed levers having their upper ends bent at right angles to form a pair of opposing grab members, a bow spring having an end secured to the 60 upper end of the pole and its other end notched to slip into locked engagement with the stud pivot and a flexible pulling element that connects at the upper end with the fulcrum stud pivot and whose lower end extends down to the handle end of the pole, a trigger lever pivotally mounted in the said handle end of the pole and a flexible connection that joins the trigger lever with the 65 said pull member.

4. An appliance for the purpose described comprising a pole, toggle levers pivotally mounted on the upper end of the pole, said levers including crossed members having 70 portions bent at right angles to form grab arms, a stud pivot that forms the fulcrum for the crossed members, a bow spring projected from the upper end of the pole and having its upper end interlocked with the stud pivot, and a flexible 75 pull member that extends to the lower end of the pole and has its upper end connected with the pivot stud, all being arranged whereby by drawing on the pull member the levers are extended to open the grab jaws 80 and apply tension to the bow spring, the said bow spring tending to normally move the toggle levers and the grab arms to the crossed or grabbing position.

FRANK DERDITS.
